UNITED STATES PATENT OFFICE.

OTTO HEINIGKE, OF NEW Utrecht, NEW YORK, ASSIGNOR TO THE HARTFORD CARPET COMPANY, OF HARTFORD, CONNECTICUT.

DESIGN FOR A CARPET.

SPECIFICATION forming part of Design No. 14,847, dated October 16, 1883.

Application filed July 23, 1883. Term of patent 3½ years.

To all whom it may concern:

Be it known that I, OTTO HEINIGKE, of New Utrecht, New York, have invented a new and original Design for Carpets, of which the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view of a carpet showing my new design.

The design consists of a system of leaf-sprigs of three leaves each, and of flower-sprigs of three flowers each, irregularly disposed over a ground that is filled with small leaf and bud forms on small irregular connecting stems, all as clearly shown in the photograph.

I claim—

The design for a carpet, consisting of the design substantially as shown and described.

OTTO HEINIGKE.
